SUPPORTER FOR WEARING APPAREL

Filed Jan. 23, 1930

UNITED STATES PATENT OFFICE

OTTO G. STOFFREGEN, OF CHICAGO, ILLINOIS

SUPPORTER FOR WEARING APPAREL

Application filed January 23, 1930. Serial No. 422,824.

The present invention relates generally to supports for wearing apparel. More particularly the invention relates to that type of support which is in the form of a shoulder strap and is adapted for use in connection with corsets, brassières and similar garments.

One object of the invention is to provide a shoulder strap which is generally of new and improved construction and embodies novel devices whereby the ends thereof may be connected to the garment that is to be supported.

Another object of the invention is to provide a shoulder strap of the aforementioned character in which the attaching devices are connected to loops on the ends of the strap and are readily removable so that the strap may be washed without the devices.

A further object of the invention is to provide a shoulder strap which is so constructed that the length thereof may be readily varied in order to support the garment to which it is attached in any desired position.

Other objects of the invention and the various advantages and characteristics of the present shoulder strap construction will be apparent from a consideration of the following detailed description.

The invention consists in the several novel features which are hereinafter set forth and are more particularly defined by the claim at the conclusion hereof.

In the drawing which accompanies and forms a part of this specification or disclosure and in which like numerals of reference denote corresponding parts throughout the several views: Fig. 1 is a perspective of a garment having applied thereto a pair of shoulder straps embodying the invention.

Fig. 2 is a longitudinal section through the fastening devices at the ends of one of the straps. Fig. 3 is a detail of the fastener for connecting the elastic loop of the strap to the garment. Fig. 4 is a detail of the fastener for connecting the adjustable loop of the strap to the garment. Fig. 5 is a detail of a modified form of fastening device.

The shoulder strap which forms the subject matter of the invention is designated in

the drawing by the reference letter B and is adapted in conjunction with another strap of similar construction to support a corset or similar garment A. It is designed to extend over the shoulder of the wearer of the garment A and embodies at the ends thereof fastening devices C and D. These devices serve to connect the strap to the garment. The strap is formed of a strip of non-elastic ribbon b and an elastic strip b', the contiguous ends of which are sewed together as at b². The elastic strip b' is folded to form a loop b³ which is detachably connected to the fastener C. The distal end of said strip b' is sewed as at b⁴ so that the loop is closed. Strip b is folded to form a loop b⁵ which is adapted to slide and pass through fastener D. In addition to the fastening devices C and D the strap embodies a buckle E. This buckle is slidable on the strap and comprises a central cross-bar e and end bars e'. Strip b passes under the end bars and over the central bar of the buckle, so the buckle will be frictionally gripped when the strip is drawn taut. The free end of the portion of strip b which forms the loop b⁵, is folded around cross-bar e and under the contiguous portion of strip b, so that it will be frictionally and removably held in the buckle when the shoulder strap is taut. By sliding the buckle on the strap, the loop b⁵ may be lengthened or shortened to lengthen or shorten the strap and consequently it is possible to adjust the strap to the wearer, and so it will support the garment in the desired position. When the end of the loop b⁵ is withdrawn from the buckle, the latter can be slipped off the strap.

Fastener C comprises a plate c which has a transverse slot c' therein for the elastic loop b³ and a slot c² in the top of the plate to permit the loop b³ to be inserted into and removed from said slot c'. A sleeve c³, slidable on the top of the plate, is adapted to close slot c² and prevent accidental withdrawal of the loop b³ from slot c'. The lower portion of plate c is formed with an integral cylindrical tongue c⁴ in which one side c⁵ of a safety fastener c⁶ is hinged. Fastener c⁶ comprises a wire which is bent to form side 100

c⁶, a resilient pin *c⁷* and an intermediate coil *c⁸*; and a clip *c⁹* in which one end of side *c⁶* is fixedly held and the point of pin *c⁷* is removably held. Pin *c⁷* is adapted to pass through the seam or hem on the upper margin of the garment to connect fastener C detachably to the garment. This fastener exemplifies one which comprises means for detachably connecting it to the garment and means whereby it may be detachably connected to the loop *b³*. When the fastener C is removed from the garment and detached from the strap, both the strap and the garment may be readily laundered without danger of being injured by the metallic fastener.

Fastener D comprises a plate *d* which is similar in construction to the plate of fastener C, except that the slot *c²* and sleeve *c³* are omitted, because the end of strip *b*, when disconnected from the buckle, can be threaded through the closed slot *d'* of fastener D in attaching this fastener to or detaching it from the strap B. Fastener D also comprises a safety fastener *c⁵* of the same construction used in fastener C and the pin *c⁷* of this safety fastener is adapted to connect the fastener D to the seam or hem of the upper margin of the garment A.

In the use of the garment A, it is desirable to remove the strap and fasteners, particularly when the latter are formed of metal, so that the garment and strap may be readily laundered. For this purpose, the pins *c⁷* may be readily unhooked from clips *c⁹* and withdrawn from the seam of the garment. This will detach the fasteners from the garment. The fastener C may then be removed from the strap by sliding the sleeve *c³* to one end of plate C and slipping the loop *b³* of the elastic strip *b'* through slot *c²*. The fastener D may be similarly detached from the garment. By withdrawing the free end of the loop *b⁵* from the buckle E, the strip *b* may be drawn out of the slot *d'* in the plate *d* of fastener D, so that this fastener will be separated from the strap. The buckle may then be stripped from the strip *b*, so that the shoulder strap will be separated from all the metallic parts.

In the modification shown in Fig. 5, the fastener comprises a safety fastener consisting of a pin *c⁷*, coil *c⁸*, side member *c⁶* and clip *c⁹*; and a member C' which is formed of a plate of metal, and comprises an upper member *c¹¹*, a lower member *c¹²*, a hook *c¹³*, which resiliently and removably engages terminal *c¹⁴* of member *c¹²* and a cylindrical loop *c¹⁵* bent around member *c⁶*. By springing the terminal *c¹⁴* out of the hook *c¹³* an opening will be provided in member C' for the insertion and removal of a loop on the strap. This form of fastener may be used at both ends of each strap, if desired. It will also be understood that the fastener C may be used at both ends of the strap, if desired.

The shoulder strap herein disclosed and described may be manufactured at a low and reasonable cost by virtue of the fact that it consists of but a small number of parts. It is exceedingly simple in construction and is of an improved design in that the fasteners for connecting the ends of the strip to the garment may be detached from the garment and from the strip.

The invention is not to be understood as restricted to the details set forth, since these may be modified within the scope of the appended claim, without departing from the spirit and scope of the invention.

Having thus described the invention, what I claim as new and desire to secure by Letters Patent, is:

A device for connecting a shoulder strap having a looped end to a garment, comprising an elongated flat plate of metal having a longitudinal slot for receiving the looped end of the strap, and a transverse slot leading to the longitudinal slot to permit the loop to be inserted into said longitudinal slot, a cylindrical shaped tongue connected to and projecting laterally from one side of the plate, a safety pin for attachment to the garment having a portion thereof extending through and connected pivotally to the tongue, and a member slidably mounted on the plate for closing the transverse slot.

Signed at Chicago, Illinois, this 2d day of January, 1930.

OTTO G. STOFFREGEN.
